UNITED STATES PATENT OFFICE.

WILLIAM F. CROWELL, OF PROVIDENCE, RHODE ISLAND.

ENVELOP.

1,052,322.

Specification of Letters Patent. Patented Feb. 4, 1913.

Application filed March 28, 1912. Serial No. 686,823.

To all whom it may concern:

Be it known that I, WILLIAM F. CROWELL, a citizen of the United States, and a resident of Providence, in the county of Providence and State of Rhode Island, have invented a new and Improved Envelop, of which the following is a full, clear, and exact description.

The object of the invention is to provide a new and improved envelop made from a sheet of paper of uniform width thus saving paper material in the manufacture of the envelop, dispensing with the use of special dies to form the blanks, and allowing the formation of envelops of different sizes from a sheet of the same width.

For the purpose mentioned use is made of a blank formed of a strip of paper or other envelop material of a uniform width and provided with means to form foldable sections adapted to be fastened together so as to produce a sectional front and a sectional back.

A practical embodiment of the invention is represented in the accompanying drawings forming a part of this specification, in which similar characters of reference indicate corresponding parts in all the views.

Figure 1 is a plan view of a blank for forming the envelop; Figs. 2 and 3 are like views of the same showing the successive steps in folding the sections; Fig. 4 is a front face view of the envelop with the sealing flap in open position; Fig. 5 is a rear view of the same; Fig. 6 is a like view of the envelop after being sealed; Fig. 7 is an enlarged cross section of the same on the line 7—7 of Fig. 5; Fig. 8 is a plan view of a modified form of a blank for forming an envelop without the sealing flap; Fig. 9 is a like view of the same partly folded; Fig. 10 is a face view of the envelop formed from the blank shown in Figs. 8 and 9; Fig. 11 is an enlarged cross section of the same on the line 11—11 of Fig. 10; Fig. 12 is a perspective view of one of the lower corners of the envelop prior to folding the parts into final position; Fig. 13 is a cross section of the same on the line 13—13 of Fig. 10; Figs. 14, 15 and 16 are plan views of blank strips from which the blanks are cut for making envelops of different forms; and Figs. 17, 18 and 19 are rear face views of the envelops produced from the blanks shown in the corresponding Figs. 14, 15 and 16.

The envelop is formed from a blank A of

uniform width and folded along the lines or creases or scores B arranged to form triangular sections C, D, E, F and G, of which the section C forms the sealing flap and the sections D and F form the front of the envelop while the sections E and G form the back of the envelop on folding the parts as indicated in Figs. 2 and 3. In order to permit convenient folding along the lines B indicated and to provide overlapping edges the top and bottom edges of the blank A are provided with notches H, H', and a similar notch H² is arranged in the bottom edge of the blank A at the points indicated in Fig. 70 1 and the lower corners are cut off as shown at H³ and H⁴. The sealing flap C is provided with gummed margins I and the section F is provided with a gummed margin I', and a similar gummed margin I² is 75 formed on the section G, so that when the parts are folded the section F overlies the section D and is fastened thereto by the gummed margin I' and the section G is fastened to the back section E by the gummed 80 margin I²; after the envelop is filled it can be sealed by the sealing flap C in the usual manner.

The blanks A are cut from a continuous strip of paper and the creases may be differently arranged, as will be readily understood by reference to Figs. 14, 15 and 16, to form envelops of different shapes and sizes (see Figs. 17, 18 and 19) without varying the width of the strip from which the 90 blanks are cut. It is understood that in either case the envelopes are formed in the manner above described in reference to Figs. 1 to 7.

In the modified form shown in Figs. 8 to 13, use is made of a blank A' of uniform width throughout its length, and the blank is provided with creases B' to divide the blank into sections J, K, L and N, which when folded form an envelop having a sectional front and a sectional back, the sectional front consisting of the sections N and K, and the sectional back consisting of the sections L and J. The section N is provided with a gummed margin O for fastening the overlapping edges of the sections K and N together, and the section J is provided with a gummed margin O' for fastening the overlapping edges J and L together, as plainly indicated in the drawings. 110 In this case, the sealing flap previously described in reference to Figs. 1 to 7 is dis-

pensed with and the envelop is open at the top.

Instead of providing the blank A' with notches, the inner corners of the envelop 5 may have the portions K' and L' of the sections K and L doubled up, as plainly indicated in Figs. 10, 12 and 13, so as to provide strong reinforced corners.

From the foregoing it will be seen that 10 in either form of the envelop the front and the back of the envelop are made in sections fastened together, and the envelop is produced from blanks cut from strips of paper of uniform width without wasting any of 15 the paper material.

It is understood that in practice the blank is folded in the manner described by a suitably constructed folded machine.

Having thus described my invention, I 20 claim as new and desire to secure by Letters Patent:

1. An envelop, comprising a front made of sections fastened together along overlapping diagonal edges, and a back made 25 of sections fastened together along overlapping diagonal edges.

2. An envelop, comprising a front made of two sections fastened together along over-

lapping diagonal edges, a back made of two sections fastened together along overlapping 30 diagonal edges, and a sealing flap integral with one of the front sections.

3. An envelop formed from a rectangular sheet of paper and comprising a front having two triangular sections fastened together 35 along overlapping diagonal edges, and a back having two triangular sections integral with the said front sections and fastened together along overlapping diagonal edges.

4. An envelop formed from a rectangular 40 sheet of paper and comprising a front having two triangular sections fastened together along overlapping diagonal edges, a back having two triangular sections integral with the said front sections and fastened together along overlapping diagonal edges, 45 and a sealing flap integral with one of the front sections and adapted to be fastened to the back sections.

In testimony whereof I have signed my 50 name to this specification in the presence of two subscribing witnesses.

WILLIAM F. CROWELL.
